Primary Examiner — Dana Meyrow(74) *Attorney, Agent, or Firm* — Calfee, Halter & Griswold LLP(57) **CLAIM**

We claim the ornamental design for a bottle, as shown and described.

DESCRIPTION

FIG. 1 is a top, perspective view of a bottle, showing the new design;

FIG. 2 is a bottom, perspective view of the bottle of FIG. 1; FIG. 3 is a front side view of the bottle of FIG. 1;

FIG. 4 is a left view of the bottle of FIG. 1;

FIG. 5 is a top view of the bottle of FIG. 1; and,

FIG. 6 is a bottom view of the bottle of FIG. 1.

The broken lines in the drawings illustrate the portions of the bottle that form no part of the claimed design.

1 Claim, 3 Drawing Sheets(56)
